UNITED STATES PATENT OFFICE.

FRANK MILFORD WADSWORTH, OF MINNEAPOLIS, MINNESOTA, ASSIGNOR TO HIRAM D. WOOD, JR., AND THEODORE J. BUERGER, BOTH OF MINNEAPOLIS, MINNESOTA.

NECKTIE-SUPPORT.

1,004,830.

Specification of Letters Patent.

Patented Oct. 3, 1911.

Application filed December 20, 1909. Serial No. 534,053.

To all whom it may concern:

Be it known that I, FRANK MILFORD WADSWORTH, a citizen of the United States, residing at Minneapolis, in the county of 5 Hennepin and State of Minnesota, have invented a certain new, and useful Improvement in Necktie-Supports, of which the following is a specification.

My invention relates to supports for neck-ties, and has for its object the production of 10 a device that will aid the wearer of the necktie in forming a knot and will afterward serve to maintain the knot and hold the necktie in its proper place on the collar.

15 The improved support consists essentially of a short tubular body, preferably of thin sheet-metal, having a lip depending from the top of the front side.

20 My improvement is illustrated in the accompanying drawings, in which—

Figure 1 is a perspective view of a knotted necktie provided with my improved support which is indicated by dotted lines. Fig. 2 is a front view and Fig. 3 a rear view of 25 the supporter. Fig. 4 is a central vertical section of the same on the line α — α of Fig. 2. Fig. 5 is a transverse section on the line ε — ε of Fig. 3. And Fig. 6 is a plan view of the device.

30 The device consists of a tubular body, designated 1, formed of thin but stiff sheet-metal or other suitable material. This body is shown as tapering somewhat from top to bottom and elliptical in cross-section, and 35 such is the preferred shape, but it may be of equal diameter throughout and round, or of other suitable shape, if desired. A lip 2 is formed or secured at the upper front edge of the tube and bent down to position 40 practically parallel with the side of the tube. In the rear wall a relatively long longitudinal slot 3 is formed.

The device is adapted for use with neckties that are tied by the wearer, and especially ties of the kind commonly called 45 "four-in-hand." In applying the device one end (the narrower end, if the tie is of the four-in-hand kind) is passed downwardly

through the tube a proper distance. If the end of the tie does not freely pass through 50 the tube access to it through the slot 3 may be had to aid in pushing it onward. Then, after the tie has been placed around the collar, the free portion is passed across the front of the support between it and the lip 55 or hook 2, which prevents it from slipping upward, and then folded around the support and the free end passed through the loop downwardly in the usual way to form a knot, and the ends are then pulled to 60 tighten the knot as much as desired. The manner of tying the knot is the usual one, the support aiding in making the knot smooth and regular, and afterward serving to hold the tie up to its place and prevent 65 the knot from loosening. It should be understood, of course, that after the knot is formed the supporting device is entirely covered and hidden by the folds of the knot.

Having described my invention, what I 70 claim and desire to secure by Letters Patent is—

1. A necktie support comprising a tubular body having a longitudinal slot in its rear portion and a hook provided on its 75 upper front portion, said support being formed of a single piece of metal and being separable from and formed independently of the tie with which it is to be used.

2. A necktie support comprising a tapering tubular body having a diamond shaped closed longitudinal slot in its rear portion and a hook provided on its upper front portion, said support being formed of a single piece of metal and being separable 85 from and formed independently of the tie with which it is to be used.

In testimony whereof I have signed my name to this specification in the presence of two subscribing witnesses this 19th day of 90 November, 1909.

FRANK MILFORD WADSWORTH.
